UNITED STATES PATENT OFFICE.

SIGWALD C. GRUNLEE, OF CHICAGO, ILLINOIS.

STOP MECHANISM FOR BLANK-FEEDING MACHINES.

Original application filed October 9, 1922, Serial No. 593,332. Divided and this application filed September 6, 1924. Serial No. 736,267.

To all whom it may concern:

Be it known that I, SIGWALD C. GRUNLEE, a citizen of the United States, and a resident of Chicago, in the county of Cook and 5 State of Illinois, have invented Improvements in Stop Mechanism for Blank-Feeding Machines, of which the following is a specification.

This invention relates to stop mechanism 10 for blank feeding machines.

The present application is filed as a division of an application for U. S. Letters Patent heretofore filed by me in the Patent Office on the 9th day of October 1922, Serial No. 593,332, in which an automatic stop mechanism embodying my invention and improvements is fully shown and described as embodied in a machine for separating, feeding and gathering signatures in book 20 binding, but is not therein separately claimed.

The stop mechanism which forms the subject-matter of the present application, is also shown as embodied in a machine particularly designed and adapted for separating, feeding and gathering signatures in book binding. This particular use or application is, however, merely illustrative and I do not desire to limit myself thereto, nor 25 to use for any particular purpose, as my improved stop mechanism admits of a wide range of adaptation and use.

The object of the present invention is to provide an improved stop mechanism for 30 blank separating and feeding machines which will be simple in construction, strong, durable and effective and dependable in operation.

To effect the objects of the invention, a stop mechanism embodying my invention and improvements comprises the various features, combinations of features and details of construction hereinafter described and claimed.

In the accompanying drawings, in which my invention is fully illustrated.

Figure 1 is a side view of a blank separating and feeding machine equipped with stop mechanism embodying my invention and improvements, said machine forming a unit of a machine for separating, feeding and gathering signatures in book binding, parts of the frame and the driving shafts being shown in section.

Figure 2 is an enlarged face view of the feed and caliper rolls forming parts of the

feed and stop mechanism of the machine, from the right side of Fig. 1.

Figure 3 is a fragmentary elevation from the right side of Fig. 2.

Figure 4 is a detached top plan view of the starting, stopping and tripping mechanism of the machine.

Figure 5 is a front elevation of the mechanism shown in Fig. 4.

Figure 6 is an end view from the position 6-6, Fig. 4.

Figure 7 is a detached sectional end view on the line 7-7 of Fig. 4; and

Figure 8 is a fragmentary view showing means for driving the feed and caliper rolls.

In the drawings, a stop mechanism of my invention is shown as applied to a machine for separating, feeding and gathering book signatures preparatory to binding them into book form, said machine being fully shown and described in my said prior application, Serial No. 593,332, of which the present application is a division, and to which reference is made for a description of parts and features herein shown but not fully described.

Describing the invention with reference to the drawings, A designates the main frame of the machine, B a separating and gathering unit mounted on said main frame, of which there may be any desired number, all duplicates of each other, and C, C¹, C², shafts which are continuous from end to end of the machine, and which are mounted in suitable bearings in the frame A.

In operation, the shaft C, which may be designated the main driving shaft of the machine, is rotated continuously in the direction indicated by the arrows, Fig. 1, by means of suitable driving connection with a source of power, not shown, said driving connection, comprising a counter-shaft which is driven by means of a belt applied to tight and loose pulleys 1 and 2 thereon. Said belt is adapted to be shifted from one pulley to the other by a belt shifter 3, of any usual or desired construction.

Oscillating movement is adapted to be imparted to the shaft C¹, by suitable driving connection with the shaft C.

The shaft C² is free to oscillate in its bearings, and oscillating or rocking movement is adapted to be imparted thereto in the operation of the machine, from the shaft C by a cam 4 secured to said shaft C, which impinges upon a stud 5 on an arm 6 se-

cured to the shaft C², an anti-friction roller 7 being preferably mounted on said stud. The arm 6 is designed and adapted for tripping the stop mechanism, presently described, and in practice, an arm 6 is provided in association with each separating, feeding and gathering unit B, the relation being such that whenever the stop mechanism of any unit is tripped, the whole machine will be stopped.

In accordance with usual practice, the pack of blanks, indicated at D, Fig. 1, specifically book signatures, are contained in a pack-box, designated as a whole D¹, from which, in the operation of the machine, the bottom signatures are withdrawn singly by suitable means provided for the purpose and are deposited upon a table 8, from which they are delivered to the gathering mechanism, not shown, by the feed mechanism, consisting, as shown, of two sets of rolls, each comprising upper rolls 9 and lower rolls 10. The upper rolls 9 of each set are secured to shafts 11 and 12, rotatably mounted in bearings in the frame of the separating unit B. The lower feed rolls comprise a front set of rolls, which are secured to a shaft 13 rotatably mounted in journal boxes 14 slidably fitted to slots 15 formed in bearing standards 16 secured to the main frame of the machine. To permit the feed rolls of each unit to accommodate themselves to the thickness of the signatures or other blanks to be fed thereby, which may vary, separate shafts 13 are provided for each unit, said shafts being maintained at the upper limit of their movement corresponding to contact of the feed rolls 10 thereon with the front set of feed rolls 9, by springs 17 inserted between the under sides of the journal boxes 14 and the bottoms of the slots 15 to which said journal boxes are fitted.

The lower feed rolls 10 also comprise a rear set of feed rolls which are rotatably mounted on studs 18 secured in the outer ends of arms 19, formed in the inner ends of which are bearings fitted to turn freely on a shaft 20 secured in fixed bearings in the frame of the separating and gathering unit B.

The rear set of lower feed rolls 10 is held yieldingly in contact with the opposed upper feed rolls by springs 21 inserted between the outer ends of the arms 19 and the main frame of the machine. Also, to provide necessary traction of the feed rolls with the blanks to be fed, all of the lower feed rolls 10 are provided with rubber treads 22.

Separate shafts 11, 12 and 20 are preferably provided for each separating and gathering unit B.

Both sets of upper feed rolls 9 and the front set of lower feed rolls 10 are positively driven from the main driving shaft C of

the machine in the following manner:—Secured to the shafts 11, 12 and 13 respectively, so as to rotate therewith are gears 23, 24 and 25, the gears 23 and 25 meshing directly with each other while the gears 23 and 24 mesh with an intermediate gear 26 secured to a shaft 27 mounted in bearings in the frame of the separating and gathering unit B and which is continuous from end to end of the machine. The gear 26 is positively driven from the shaft C by means of a gear 26¹ secured to the shaft 27, which meshes with a gear 26² secured to the hub of a sprocket wheel 28 rotatably mounted on a stud 28¹ secured in a standard 28² on the extreme end of the main frame of the machine. The sprocket wheel 28 is driven from the shaft C by means of a chain belt 29 adjusted to said sprocket wheel 28 and to a sprocket wheel 30 secured to the shaft C. A simple and preferable construction consists in positioning the sprocket wheels 28 and 30 and operating parts directly associated therewith beyond the end of the main frame of the machine. The use of the gear 26² is necessary to secure rotation of the feed rolls 9 and 10 in the proper direction.

The gearing connecting the driving shaft C with the shaft 27 affords convenient means for speeding up the feed rolls to insure delivery of signatures or other blanks into the gathering chute, not shown, with the time limited, so that they will clear the arms of the gathering mechanism and whereby, also, impact of said signatures or other blanks with the outer side wall of the gathering chute will "jog" the blanks of each pack.

The rear set of lower feed rolls 10 are friction driven by contact with the rear set of upper feed rolls 9, or with the blanks as they are fed between said feed rolls.

As the blanks are fed from the table 8 to the gathering mechanism, not shown, they are supported by a skeleton structure consisting, as shown, of rods or wires 31 and 32, which are positioned between the feed rolls and form an extension of said table 8.

In order to prevent defective signatures from being incorporated to the bound book, which would necessarily result in a defective book, my improved machine comprises a stop mechanism constructed and arranged to automatically stop the machine whenever a signature either thicker or thinner than the normal thickness of the signatures on which any separating and gathering unit B is operating at a given time, passes into the feed rolls 9 and 10, which normal thickness can vary only within very narrow limits, represented by the thickness of the thinnest sheet of said signatures.

As shown, the construction and operation of said stop mechanism is as follows:—

Rotatably mounted in bearings in brackets

33 secured to the rear upper edges of the frame of the separating and gathering unit B, is a shaft 34, which extends from end to end of the machine and is common to all of 5 the units B, secured to which is an arm 35 which is connected with an arm 36 applied to the belt shifter 3 by a rod 37. As shown, said rod 37 comprises sections 37¹, 37², the adjacent ends of which are pivoted to studs 10 secured in a sleeve or collar 37³ rotatably mounted on the shaft C¹.

Applied to the shaft 34 is a spring 38 adapted to maintain said shaft and belt shifter 3 in positions corresponding to engagement of the driving belt with the loose pulley 2, means being also provided for relieving said shaft 34 from the tension of the spring 38 and for shifting the driving belt from the loose to the tight pulley, when it 20 is desired to operate the machine.

As shown, the means for applying said spring 38 to said shaft 34 and for relieving said shaft from the tension of said spring are as follows:—Pivoted upon the shaft 34 25 is a lever 39, one end of the spring 38 being secured to the hub of said lever and its opposite end to the adjacent bearing bracket 33, and said lever 39 having operative engagement with the shaft 34 by means of pins 40 and 41 secured in said lever and shaft, respectively, the relation being such that pivoted movement of the lever 39 to retract the pin 40 secured therein from the pin 41 secured in the shaft 34 will relieve 30 said shaft 34 from the tension of the spring 38 and will permit movement of said shaft in a direction to shift the driving belt from the loose pulley 2 to the tight pulley 1.

In accordance with my invention, also, 40 means are provided for locking the lever 39 in position to relieve the shaft 34 from the tension of the spring 38. As shown, said locking means or mechanism consists of an arm 42 secured to a shaft 43 mounted in brackets 44 forming extensions of the brackets 33, a projection 45 on the free end of which is adapted to engage a shoulder 46 formed on a fin 47 on the lever 39, said projection 45 preferably consisting of a stud 45 secured in the said lever arm and an anti-friction roller mounted on said stud. Said shaft 43 will preferably be maintained 50 yieldingly in position corresponding to engagement of said projection 45 with the shoulder 46 on the lever 39 by a spring 48 applied thereto. As shown, said spring is a coiled spring which surrounds the shaft 43, one end of which is connected to one of the brackets 44 and the other to a collar 49 secured to said shaft, preferably by a set screw so as to provide for adjusting the tension of said spring.

When the shaft 34 is relieved from the 55 tension of the spring 38, movement is adapted to be imparted to the belt shifter to shift

the driving belt to a tight pulley by a spring applied thereto, thus starting the machine. As shown, said spring consists of a coiled spring 50 which surrounds the shaft 34, opposite ends of which are secured, respectively, to a collar 51 on said shaft 34 and to the adjacent bearing bracket 33, said collar 51 being preferably secured to the shaft by means of a set screw, thus providing for adjusting the tension of the spring 50. 70

As previously stated, in the contemplated operation of the machine, the spring 38, when released, is designed to turn the shaft 34 so that, through the arm 35, the rod 37 and the belt shifter 3, the driving belt will be shifted from the tight pulley 1 to the loose pulley 2, thus stopping the machine. With the construction described, it is obvious that, to render said spring 38 effective for its designed purpose, it will be necessary that said spring shall be sufficiently strong to overcome the tension of the spring 50, to depress the weight of the connecting rod 37 and to overcome the friction of the various operative parts of the belt shifting mechanism. 80

To start the machine, it is merely necessary to turn the lever 39 into position to effect engagement of the projection 45 on the arm 42 with the shoulder 46 on the fin 47 on said lever, thus imparting movement to the belt shifter 3 to shift the belt from the loose pulley 2 to the tight pulley 1; and, to stop the machine, it is merely necessary to disengage the projection 45 from the shoulder 46, permitting the spring 38 to turn the lever 39 into the position shown in Fig. 1 and, through the pins 40, 41, turning the shaft 34 in the direction to shift the belt from the tight pulley to the loose pulley. 90

My improved machine also comprises an automatic trip mechanism, the construction and operation of which is as follows:

Secured to the shaft 43, so as to turn therewith is a trip lever, designated as a whole E, comprising a fixed arm 52 pinned or otherwise rigidly secured thereto, and a member 53 attached to the under side of said fixed member so as to be adjustable endwise thereof. Formed on the outer end of said adjustable member 53 are flanges 54, which embrace the sides of the fixed member 52, secured to the top edges of which is a strap 55 which extends over the top of said fixed member. The opposite end of said adjustable member 53 is adapted to be secured to the fixed member 52 by a clamping screw 56 which extends through a slot formed therein and has screw threaded engagement with a hole formed in said fixed member 52. Adjustment of the member 53 endwise of the fixed member 52 is adapted to be effected by means of an adjusting screw 58 which has screw threaded engagement with a hole 100

formed in the end of the fixed member 52 and which is mounted to turn freely in a slot 59 formed in an upwardly extending lug or projection 60 formed on the inner end of 5 said adjustable member 53, said adjusting screw being secured against endwise movement relative to said adjustable member by flanges 61 thereon, which are adapted to embrace opposite sides of said lug or projection 10 60.

Co-operating with the trip lever E is a push-bar 62, rigidly secured to the upper end of which is a forked plate 63 the forked ends 64 of which are adapted to play through 15 holes 65 formed in the flanges 54 on the adjustable member 53 of the trip lever.

The push-bar 62 is mounted so as to admit of limited endwise movement by means of roller studs 66 and 67 which extend 20 through slots 68 and 69 formed in the lower end of said push-bar.

The stud 66 is secured in the frame of the separating and gathering unit B and the stud 67 is secured in the outer end of an arm 25 70 secured to the shaft 20, see particularly Fig. 3. To provide for adjusting the angular position of the lever arm 70 on the shaft 20, said lever arm is preferably clamped to said shaft by means of a clamping screw 71, the shaft bearing in said lever being preferably slotted as shown at 71¹ to permit 30 said bearing to be compressed upon the shaft 20.

Reciprocating movement is adapted to be imparted to the push-bar 62 by a link 72 pivotally connected to the lower end of said push-bar and to the outer end of the rock-arm 6.

With the construction described, it is obvious that at each revolution of the shaft C, 40 the cam 4 on said shaft, through the roller-stud 5 on the arm 6 will operate to impart oscillatory movement to the arm 6, which, through the link 72 will impart reciprocating movement to the push-bar 62, in the manner desired.

My improved automatic stop mechanism also comprises caliper rolls 73 and 74, of 50 which the roll 73 is secured to the shaft 12 so as to rotate therewith and the roll 74 is mounted at the other end of an arm 75 secured to rotate with the shaft 20, preferably in such manner as to be angularly adjustable thereon. As shown, the shaft bearing in 55 said brackets 75 is split and said arm is adapted to be clamped to said shaft by means of a clamping screw, in a familiar manner.

With the described construction, it is obvious that as signatures and other blanks are 60 delivered from the table 8 to the gathering chute, they will pass between the caliper rolls 73, 74, which will operate, in an obvious manner, to force the lower roll 74 downwardly away from the upper roll and

will impart limited rocking movement to the shaft 20—which will vary with the thickness of the signatures or other blanks—which will, in turn, impart oscillation to the arm 70 secured to said shaft, and through it to the push-bar 62 and to the fork 63 secured to the upper end thereof. 70

The cam on the shaft C is so timed with reference to the feeding of the signatures or other blanks, that the upward reciprocation of the push-bar 62 will occur simultaneously with the feeding of the signatures or other blanks from the table 8 to the gathering chute and their passage between the caliper rolls 73, 74. 80

Preliminary to starting a run, the stop mechanism is adjusted so that when a signature or other blank of normal thickness is between the caliper rolls 73, 74, the ends 64 of the fork 63 will pass freely through the holes 65 in the trip lever E. Such adjustment is made by first securing the arm 70 to the shaft 20 in position to effect approximate registration of said forked ends with the holes or openings 65 with a signature between the caliper rolls; exact registration being then effected by adjusting the slide member 53 of the trip lever E endwise into proper position by means of the adjusting screw 58. Exact registration having 90 been effected, the member 53 is then secured in fixed adjustment by the clamping screw 56. 95

Having adjusted the push-bar to effect registration of the forked ends 64 with the holes 65 in the trip-lever E, the lever 39 is turned against the force of the spring 38 applied to the shaft 34 to start the machine, in which position it is secured by engagement of the projection 45 on the lever 42 with the shoulder 46 on the fin 47, operation of the machine continuing without interruption so long as the signatures or other blanks passing through the feed and caliper rolls are of normal thickness. 100

If, however, a signature either thicker or thinner than the normal thickness of the signatures enters the caliper rolls 73, 74, a corresponding error will occur in the angular movement of the push-bar 62 which error will be multiplied several times at the forked ends 64, due to the fact that the distance between the guide studs 66 and 67 is only about one sixth of the distance between the fixed pivot stud 66 and the extreme upper ends of the forked end. This departure from normal in the operation of the push-bar 62 will bring the forked ends 64 out of register with the holes 65 in the trip-lever E so that, as said push-bar is raised by the action of the cam 4 on the driving shaft C, causing the forked ends 64 to strike the under side of said trip-lever at one side or the other of said holes 65, as the defective signature is thicker or thinner than 110 115 120 125 130

normal, thus turning said trip lever and with it the shaft 43 pivotally to disengage the projection 45 from the shoulder 46, thereby releasing the shaft 34 and permitting it to turn under the tension of the spring 38 to shift the driving belt from the tight pulley 1 to the loose pulley 2 and stop the machine in the manner contemplated, before the defective signature is delivered into the gathering chute, thus permitting it to be removed and replaced by a perfect signature.

In accordance with my invention, also, the stop mechanism is adapted to be tripped manually by means of a hand lever 76 formed on the trip arm 42.

I claim—

1. In a machine of the type specified, the combination of blank feeding means, driving means therefor, and starting and stopping means comprising a starter, a spring applied thereto adapted to turn on the driving means, a shaft, means connecting said shaft with the starter, a lever mounted to turn on said shaft, a spring applied to said lever, pins secured in said shaft and lever, the relation being such that when said lever is free to turn on said shaft said pins will transmit the tension of the spring applied to said lever to said shaft and will turn said shaft to throw off the starter and stop the machine, and the relation being such also that when said lever is turned to relieve said shaft from the tension of the spring applied to said lever, the starting spring applied to the starter will turn on said driving means and start the machine, and will also turn the shaft on which said starting lever is mounted to advance the pin secured therein toward the pin secured in said lever, whereby when said lever is released the spring applied thereto will turn said lever to cause the pin secured therein to engage the pin secured in said shaft, the spring applied to said lever being sufficiently strong to rotate said shaft to turn off the starter and stop the machine, a lock arm pivoted adjacent to the lever on the starter operating shaft, and a projection thereon adapted to interlock with a shoulder on said lever to secure said lever in position to relieve the starter operating shaft from the tension of the spring applied to said lever, thus permitting the spring applied to the starter to actuate the same to start the machine.

2. In a machine of the type specified, the combination of blank feeding means, driving means therefor, and starting and stopping means comprising a starter, a spring applied thereto adapted to turn on the driving means, a shaft, means connecting said shaft with the starter, a lever mounted to turn on said shaft, a spring applied to said lever, pins secured in said shaft and lever,

the relation being such that when said lever is free to turn on said shaft said pins will transmit the tension of the spring applied to said lever to said shaft and will turn said shaft to throw off the starter and stop the machine, and the relation being such also that when said lever is turned to relieve said shaft from the tension of the spring applied to said lever, the starting spring applied to the starter will turn on said driving means and start the machine, and will also turn the shaft on which said starting lever is mounted to advance the pin secured therein toward the pin secured in said lever, whereby when said lever is released the spring applied thereto will turn said lever to cause the pin secured therein to engage the pin secured in said shaft, the spring applied to said lever being sufficiently strong to rotate said shaft to turn off the starter and stop the machine, a lock arm, a rock shaft to which said rock lever is secured, and a projection on said lock arm arranged to engage a shoulder on the starting lever and to secure said starting lever in position to relieve the starter operating shaft from the tension of the throw-off spring.

3. In a machine of the type specified, the combination of blank feeding means, driving means therefor, and starting and stopping means, means for maintaining said driving means yieldingly "off", means for turning on the driving means against the force of said stopping means, locking means adapted for maintaining said driving means "on", and a trip mechanism rendered operative by variation in the thickness of a blank for releasing the stopping means, the starting and stopping means comprising a starter, a spring applied thereto adapted to turn on the driving means, a shaft, means connecting said shaft with the starter, a lever mounted to turn on said shaft, a spring applied to said lever, pins secured in said shaft and lever, the relation being such that when said lever is free to turn on said shaft said pins will transmit the tension of the spring applied to said lever to said shaft and will turn said shaft to throw off the starter and stop the machine, and the relation being such also that when said lever is turned to relieve said shaft from the tension of the spring applied to said lever, the starting spring applied to the starter will turn on said driving means and start the machine, and will also turn the shaft on which said starting lever is mounted to advance the pin secured therein toward the pin secured in said lever, whereby when said lever is released the spring applied thereto will turn said lever to cause the pin secured therein to engage the pin secured in said shaft, the spring applied to said lever being sufficiently strong to rotate said shaft to turn off the starter and stop the machine, a lock arm, a rock shaft to which said rock lever is secured, and a projection on said lock arm arranged to engage a shoulder on the starting lever and to secure said starting lever in position to relieve the starter operating shaft from the tension of the throw-off spring.

lever, a rock shaft to which said lock lever is secured, and a projection on said lock lever arranged to engage a shoulder on the starting lever and to secure said starting lever in position to relieve the starter operating shaft from the tension of the throw-off spring, and the trip mechanism comprises caliper rolls, one of which is rotatably mounted on an arm secured to a rock shaft, 5 a trip lever secured to the rock shaft to which the lock lever applied to the starting lever is secured, a push bar, means for supporting said push bar so that it will admit both of reciprocating and oscillating movement, means for imparting reciprocating movement to said push bar, the upper end of said push bar being constructed and arranged to play through a hole formed in the trip lever when the end of said push bar 10 is in register with said hole, the means for supporting said push bar comprising studs which engage slots formed in said push bar, comprising a fixed stud and a stud secured in a lever arm secured to the caliper roll rock 15 shaft, the relation being such that oscillation of said rock shaft will impart oscillation to said push bar about the fixed supporting stud, means for effecting relative adjustment of said push bar and the trip 20 lever to effect registration of the upper end of said push bar with the hole formed in said trip lever when a blank of normal thickness passes between said caliper rolls, oscillation of said push bar corresponding to variations 25 in the thickness of the blanks in excess of prescribed limits causing the end of said push bar to strike the trip lever at one side or the other of the hole therein and turn said trip arm together with the rock shaft 30 and lock lever releasing the starting lever 35 and stopping the machine.

4. A trip mechanism for a blank feeding machine as specified in claim 3, in which the means for imparting reciprocating movement to the push bar comprises driving and rock shafts, a cam and a lever arm secured to said shafts, respectively, a projection on said lever arm which rides on the cam on said driving shaft, and connection between 45 said lever arm and the lower end of the push bar.

5. A trip mechanism for a blank feeding machine as specified in claim 3, in which the lever arms to which, respectively, the 50 movable caliper roll and the movable stud for supporting the push bar are secured, comprise a lever arm which is angularly adjustable on the caliper roll rock shaft to provide for adjusting the push bar relatively to the hole in the trip lever.

6. A trip mechanism for a blank feeding machine as specified in claim 3, in which both rock arms secured to the caliper roll rock shaft are angularly adjustable to pro-

vide for adjusting the push bar with reference to the trip lever.

7. A trip mechanism for a blank feeding machine as specified in claim 3, in which the trip lever comprises a fixed member secured to the rock shaft and a slide member 70 in which the hole is formed through which the end of the push bar is designed to play, means for effecting adjustment of said slide member endwise of said fixed member, and means for securing said slide member to said fixed member in different adjusted positions.

8. A trip mechanism for a blank feeding machine as specified in claim 3, in which the trip lever comprises a fixed member secured to the rock shaft and a slide member in which the hole is formed through which the end of the push bar is designed to play, means for effecting adjustment of said slide member endwise of said fixed member, and means for securing said slide member to said fixed member in different adjusted positions, the means for effecting endwise adjustment of the slide member of the trip lever consisting of an adjusting screw which has screw 80 threaded engagement with a hole formed in the fixed member of said trip lever, and means for rotatably engaging said adjusting screw with said slide member against relative endwise movement.

9. A trip mechanism for a blank feeding machine as specified in claim 3, in which the trip lever comprises a fixed member secured to the rock shaft and a slide member in which the hole is formed through which the end of the push bar is designed to play, means for effecting adjustment of said slide member endwise of said fixed member, and means for securing said slide member to said fixed member in different adjusted positions, said slide member comprising flanges which embrace the sides of the fixed member of said trip lever and are proportioned to extend flush with the top thereof, and a strap 90 is secured to the upper edges of said flanges which extends over the fixed member of said trip lever.

10. A trip mechanism for a blank feeding machine as specified in claim 3, in which the trip lever comprises a fixed member secured to the rock shaft and a slide member in which the hole is formed through which the end of the push bar is designed to play, means for effecting adjustment of said slide member endwise of said fixed member, and means for securing said slide member to said fixed member in different adjusted positions comprising a slot formed in said slide member, and a clamping screw inserted 100 through said slot and which has screw threaded engagement with a hole in the fixed trip lever member.

11. A trip mechanism for a blank feed-

ing machine as specified in claim 3, in which the trip lever comprises a fixed member secured to the rock shaft and a slide member in which the hole is formed through which the end of the push bar is designed to play, means for effecting adjustment of said slide member endwise of said fixed member, and means for securing said slide member to said fixed member in different adjusted positions, the upper end of the push bar being forked and the slide member of the trip lever comprising flanges, both the forked upper ends of said push bar and the flanges on said slideable trip lever member embracing opposite sides of the fixed trip lever member, and said flanges being provided with holes through which the forked upper ends of said push bar are adapted to play, the sides of the holes in said flanges flaring upwardly from points adjacent to the lower edges of said flanges.

12. A trip mechanism for a blank feeding machine as specified in claim 2, in which the trip lever comprises a fixed member secured to the rock shaft and a slide member in which the hole is formed through which the end of the push bar is designed to play, means for effecting adjustment of said slide member endwise of said fixed member, and means for securing said slide member to said fixed member in different adjusted positions, the upper end of the push bar being forked and the slide member of the trip lever com-

prising flanges, both the forked upper ends of said push bar and the flanges on said slideable trip lever member embracing opposite sides of the fixed trip lever member, and said flanges being provided with holes through which the forked upper ends of said push bar are adapted to play, the sides of the holes in said flanges flaring upwardly from points adjacent to the lower edges of said flanges.

13. A trip mechanism for blank feeding machines as specified in claim 3, in which the distance between the studs by which the push bar is supported is appreciably less than the dimension of said push bar from the fixed stud to its free end.

14. A trip mechanism for blank feeding machines as specified in claim 3, in which the distance between the studs by which the push bar is supported is appreciably less than the dimension of said push bar from the fixed stud to its free end, and the studs which support and guide the push bar engage the same adjacent to the end thereof to which the power is applied for reciprocating the same.

In witness that I claim the foregoing as my invention, I affix my signature this 4th day of September, A. D. 1924.

SIGWALD C. GRUNLEE.
